UNITED STATES PATENT OFFICE.

CHARLES W. COOK, OF HOLYOKE, MASSACHUSETTS.

PAPER-FINISHING PLATE.

1,362,677.

Specification of Letters Patent. Patented Dec. 21, 1920.

Application filed March 5, 1919. Serial No. 280,810.

To all whom it may concern:

Be it known that I, CHARLES W. COOK, a citizen of the United States, residing at Holyoke, in the county of Hampden and 5 State of Massachusetts, have invented new and useful Improvements in Paper-Finishing Plates, of which the following is a specification.

My invention relates to improvements in 10 finishing plates used to give fancy finishes to papers such, for example, as are used for writing paper, cover paper and the like.

It is common practice to use fabrics for giving a cloth like finish to writing paper. 15 This is usually accomplished by making up what is termed a book comprising alternate layers of paper, cloth, and cardboard and then subjecting the same to high pressure in a plater press. The sheets of paper are then 20 removed, one side bearing the impression of the cloth, and the other which was in contact with the cardboard remaining smooth. This is an expensive process, special fabrics which are very costly being necessary, and 25 the life of the fabric quite short as it soon loses its rough surface.

My finishing plate produces similar results at a lower cost and is not limited to cloth finishes in the designs which may be 30 produced.

The invention comprises in general a finishing plate in which the desired pattern is impressed in a pyroxylin sheet backed up by cardboard or similar material. These 35 plates are then interlocked between sheets of paper and passed through a plater press as in the method using cloth.

To describe a specific application of my 40 invention it will be assumed that it is desired to give a fabric finish to a sheet of paper. I first have a metal plate, such as steel, copper, or zinc, etched by well known methods to give a reproduction of the desired fabric. A sheet of cardboard is then 45 placed in a press and over the cardboard is placed a thin sheet of xylonite or other commercial form of pyroxylin product. The metal plate is then placed over the xylonite and the whole subjected to pressure and 50 heat. The press is then opened and it will

be found that the impression has been transferred to the xylonite and cardboard. The heat has aided the xylonite in taking the impression and the cardboard serves as a base or reinforcing back. The heat and 55 pressure unite the xylonite and cardboard, though a binder of some sort may be used.

The drawing represents a perspective of 60 finishing plate, the impression sheet being lifted from a portion of the cardboard base.

The surface of the xylonite is hard and the impression being sharply defined a plate of this character has a long life as compared with fabric or plates made up with a paste composition. Any other material having 65 characteristics similar to pyroxylin may be employed, the term pyroxylin being used to indicate any pyroxylin-like material.

The metal plate is used to make up as 70 many finishing plates as desired, twenty usually comprising a so-called book. The finishing plates thus made are then placed in a plater press with a sheet of paper between each plate and subjected to pressure. The book is then removed and the finished 75 sheets taken out, unfinished sheets substituted and again run through the press. In this way the sheets of paper are given the desired finish.

The impression may be produced on the 80 pyroxylin sheet by means other than a metal plate, as for example, pressing a piece of cloth directly against its surface, but by means of a metal plate any design may be produced.

What I claim and desire to secure by Letters Patent is:—

1. An embossing die used as a paper finishing plate and comprising a member of pyroxylin adapted to indent or emboss a 90 fancy finish in the surface of a sheet of paper, said pyroxylin having substantially its entire surface impressed with high and low portions to impart said embossed finish to the surface of the paper. 95

2. A finishing plate for producing a fancy finish on a sheet of paper, said finishing plate comprising a backing sheet of cardboard and a covering of pyroxylin.

CHARLES W. COOK.
